VALVE FOR INTERNAL COMBUSTION ENGINES

Robert Jardine, deceased, late of Detroit, Mich.,
by Louise Smith Jardine, administratrix, Detroit, Mich., assignor to Eaton Manufacturing Company, Cleveland, Ohio, a corporation of Ohio

Application June 29, 1937, Serial No. 150,964

2 Claims. (Cl. 123—188)

This invention relates to internal combustion engines and more particularly to an improved valve for such engines.

It is well known that during the operation of internal combustion engines considerable valve trouble arises from the fact that carbon and other material collects on the valve stem and guide, particularly on and adjacent that portion of the valve stem which operates in the upper end of the guide. These deposits have a tendency to prevent the valve from seating fully, which results in overheating and burning of the valve, and, ultimately, in valve failure. Many devices have been proposed heretofore to prevent or eliminate these deposits and their attendant disadvantages, but such devices have not been generally successful or satisfactory. By the improved valve of the present invention, these difficulties are substantially overcome, as will be explained more in detail hereinafter.

It is, therefore, an object of this invention to provide novel internal combustion engine valve means in which the depositing of carbon or other material, tending to interfere with the operation of the valve, is substantially eliminated.

Another object of this invention is to provide a novel combustion engine valve having a collar or land on the stem thereof adapted to operate in a portion of the valve guide opening to prevent the deposit of material on the valve stem and guide.

A further object of this invention is to provide a novel exhaust valve for an internal combustion engine in which a land or collar, formed on the valve stem and of larger diameter than the stem, is adapted to operate in an enlargement of the valve guide opening and is so located, with respect to the head of the valve, that it will project part-way from such enlargement when the valve is in its open position.

Other objects and advantages of this invention will be apparent from the following description, when taken in conjunction with the accompanying sheet of drawings, in which

Fig. 1 is a sectional view taken through an internal combustion engine valve embodying the novel construction and through the associated valve guide;

Fig. 2 is a transverse sectional view of the valve taken as indicated by line 2—2 of Fig. 1; and

Fig. 3 is a fragmentary sectional view on the order of that of Fig. 1 but showing the land or collar of the valve stem in its extreme upper position.

In the accompanying drawing, to which more detailed reference will presently be made, there has been shown one embodiment of a novel internal combustion engine valve means, but it should be understood that the drawing is to be regarded as illustrative and that the invention may be embodied in various other internal combustion engine valves and valve arrangements.

In Fig. 1 of the drawing there is shown an engine block 10 having an annular valve seat or ring 11 disposed around an end of the passage 12, and also having a tubular portion providing a hollow valve guide 13 which extends substantially coaxially with respect to the valve seat. A valve 14, embodying the novel construction of the present invention, has a head 15 which cooperates with the valve seat 11 to control the passage 12 and a stem 17 which is adapted to be reciprocated in the opening of the guide 13 for moving the head to its open and closed positions. The present invention is especially applicable to exhaust valves and, in the embodiment here illustrated, the passage 12 may be a passage for exhaust gases and the valve 14 may be an exhaust valve. Although the invention can be readily applied to different types of valves and to valves of solid construction, the valve shown in this instance is one of the hollow type; that is, having a chamber 18 in which a quantity of metallic sodium is confined by the plug 19 and the weld 20.

To prevent the deposit of carbon or other material on the valve stem and on the valve guide, which, as mentioned above, would interfere with the proper seating and operation of the valve, the stem of the valve is provided with a land or collar 21 and the opening of the guide is provided with an enlargement 22 in which the land or collar of the valve stem operates. The land or collar is of larger diameter than the valve stem and, although it is preferably formed as an integral part of the stem, it can be made as a separate ring or sleeve and united to the stem. The diameter of the land or collar is only slightly smaller than that of the enlargement 22 so that it will operate smoothly in the enlargement and yet will have a scraping and pumping action therein. The enlargement may be formed as a counterbore in the guide 13, or may be formed by inserting a guide sleeve or bushing 23 in the guide opening as shown in Fig. 1, with the upper end of such sleeve or bushing terminating short of the upper end of the guide opening.

As collar or land 21 of the valve stem operates in the enlargement 22 of the guide opening, during reciprocation of the valve, it pre-

vents the deposit of carbon on the valve stem and guide at this point by exerting more or less of a scraping action on the guide and by producing somewhat of a pumping action which 5 tends to keep the space below the collar free of deposit forming gases and material. The collar or land is of a length and is located, with respect to the head of the valve, such that it will project part-way out of the enlargement 22, as shown 10 in Fig. 3, when the valve has been moved to its open position. In thus causing the collar or land to overrun the upper end of the guide opening, it was found that the scraping and pumping action produced thereby is more effective in eliminating or discouraging the deposit of carbon or 15 other material at this point. In addition to the scraping and pumping action already referred to, it was found that the collar or land also provides a seal around the valve stem which prevents material from traveling downwardly along 20 the valve stem and forming a deposit at a lower point on the stem and guide.

It will also be seen from the drawing that the enlargement 22 of the valve guide provides a 25 space or chamber which surrounds the valve stem beneath the land or collar 21, and that the volume of this chamber changes during the reciprocation of the land in the enlargement to thereby produce the above-mentioned pumping 30 action. During downward movement of the valve stem the volume of the chamber is reduced and any gas which may be in the chamber below the land will be subjected to compression thereby causing a "blowing" of gas upwardly past the land 35 and this will tend to prevent carbon particles from traveling downwardly past the land into the chamber therebelow.

From the foregoing description and the accompanying drawing, it will now be readily seen 40 that a novel form of internal combustion engine valve has been provided which, in use, substantially prevents the deposit of carbon or other material on the valve stem and valve guide. It will be seen further that the land or collar provided on the valve stem to operate in an enlargement of the guide opening prevents the 45 deposit of carbon or other material on the stem

and guide and thus eliminates much of the valve trouble heretofore encountered in the operation of internal combustion engines.

Although the present invention and improvement has been illustrated and described in detail, it will be understood, of course, that the invention is not to be regarded as limited to the precise construction and arrangement herein disclosed, but includes such changes and modifications as do not constitute a departure from the spirit of the invention and scope of the appended claims.

What is claimed is:

1. In combination, a valve guide having an opening with an enlargement at its upper end, 15 and an exhaust valve having a stem operable in the guide and an annular collar of larger diameter carried by the stem and operable in said enlargement for preventing the deposit of material on the stem and guide, the stem below the collar being slidable in the guide and a portion of said enlargement providing a chamber around the stem below the collar.

2. In apparatus of the character described, a valve seat, a valve guide having an opening substantially coaxial with said seat, said guide opening having an enlargement at the end thereof nearest said seat, an exhaust valve having a head adapted to engage said seat and a stem reciprocably slidable in the guide opening below 30 the enlargement for moving the head to its open and closed positions, and a collar of larger diameter than the stem and carried thereby and operable with small clearance in the enlargement of the guide opening for preventing the 35 deposit of material on the stem and guide, said collar being of a length and located relative to the head such that it will project part-way from said enlargement when the valve is in its open position and being also spaced from the lower 40 end of the enlargement whereby a portion of the enlargement provides a chamber below the collar.

LOUISE SMITH JARDINE,
Administratrix of the Estate of Robert Jardine, 45
Deceased.
